AUTOMATIC SLACK ADJUSTER MECHANISM

George B. Dorey, Westmount, Quebec, Canada, assignor to Continental Transport Appliances, Limited, Montreal, Quebec, Canada, a corporation of Canada

Application December 29, 1951, Serial No. 264,033

3 Claims. (Cl. 188—202)

The invention relates to an improved automatic slack adjuster mechanism for the brakes of railway cars and the like.

This invention constitutes an improvement over my inventions disclosed in my co-pending application, Serial No. 152,061, filed March 27, 1950, now Patent No. 2,646,139 of July 21, 1953; application Serial No. 164,871, filed May 29, 1950, now Patent No. 2,646,140; application Serial No. 179,046, filed August 12, 1950, now Patent No. 2,646,137, July 21, 1953; application Serial No. 191,625, filed October 23, 1950, now Patent No. 2,646,138; application Serial No. 208,396, filed January 29, 1951, now abandoned; application Serial No. 210,747, filed February 13, 1951, now Patent No. 2,646,141, July 21, 1953; and application Serial No. 210,748, filed February 13, 1951.

The objects of the invention among others are to provide an automatic slack adjuster mechanism which is of simple construction and available as a package unit suitable for application to various types of existing equipment without modification; to provide spring operated slack adjuster having a spring operating mechanism in which the parts are disposed in telescopic relation to render the unit self-adjusting for various lengths of push rods; to provide an improved bell crank type of operating lever mechanism for operating a screw-threaded take up device on a connection rod; to provide an improved and simplified U-shaped bracket for supporting a pivotally mounted bell crank operating lever associated with a take up device; and to provide an improved abutment structure which may be readily threaded on the stem of a push rod for energizing a spring on movement of a push rod in a brake applying direction.

For comprehension of the invention reference may be had to the accompanying drawings wherein:

Figure 1 is a plan view of a portion of a railway car showing the invention applied in connection with the brake gear of the car.

Figure 2 is a plan view on an enlarged scale of the outer end of the brake cylinder together with the spring mechanism and the push rod, the parts being shown with the brake and spring mechanism in released position.

Figure 3 is a longitudinal elevational view of the structure shown in Figure 2.

Figure 4 is a vertical sectional view taken through the spring mechanism on a line 4—4 of Figure 3.

Figure 5 is a vertical sectional view on an enlarged scale taken on a line 5—5 of Figure 1 showing the position of the bell crank operating lever in relation to the center connection and brake cylinder.

Figure 6 is a vertical sectional view on an enlarged scale taken on a line 6—6 of Figure 2.

Figure 7 is a vertical longitudinal sectional view taken through the spring mechanism on a line 7—7 of Figure 2, showing the spring mechanism in released position.

Figure 8 is a view similar to Figure 7 except that the spring mechanism is shown in partially compressed position with the locking pawl in engagement with the third retaining tooth.

Figure 9 is a view of the outer end of the mechanism shown in Figures 7 and 8 except that the pawl is shown in position of release as the spring retaining escapement operates.

Figure 10 is a view similar to Figure 9 except that the locking pawl is shown in the overbalanced non-

2

operative position assumed by the pawl during the return of the spring.

Figure 11 is a plan view on an enlarged scale of the push rod with the combined clevis and abutment applied thereto.

Figure 12 is a longitudinal elevational view of the push rod shown in Figure 11.

Figure 13 is an end elevational view of the push rod assembly shown in Figure 12 as viewed from right to left.

Figure 14 is a plan view of the push rod abutment plate.

Figure 15 is a longitudinal elevational view of the abutment plate shown in Figure 14.

Figure 16 is an elevational view of the abutment plate shown in Figure 15, as viewed from right to left.

Figure 17 is a plan view of the push rod as the combined abutment and clevis plate is being threaded thereon.

Figure 18 is a plan view of an assembly showing on an enlarged scale the screw take up device in assembled relation with the operating lever.

Figure 19 is a plan view showing the operating lever arm in assembled relation on the saddle bracket.

Figure 20 is a longitudinal elevational view of the assembly shown in Figure 19.

Figure 21 is a vertical end view of the structure shown in Figure 20 as viewed from right to left.

Figure 22 is a plan view of the pawl thrust member showing the same on an enlarged scale.

Figure 23 is a vertical end view of the thrust member shown in Figure 22.

Figure 24 is a longitudinal elevational view on an enlarged scale of the screw take up device.

Figure 25 is a vertical transverse sectional view taken through the screw take up device and on a line 25—25 of Figure 24.

In said drawings 10—10 indicates the center sill members of the car and secured thereto is a bracket 11 for supporting the airbrake cylinder 12, the latter being bolted or otherwise secured to the bracket as indicated at 13. The cylinder 12 is provided with the usual push rod 14 which is pivotally connected at 15 to the brake leverage system as indicated by the live lever 16, center rod 17 and dead lever 18.

The dead lever 18 is pivotally mounted at 19 on a bracket 20 which in turn is secured to the center sill at 21 and the respective dead and live levers are pivotally united at an intermediate location by pintles 22. Pivotally connected to the outer ends of the respective live and dead levers are top rods 24 which in turn lead to the truck (not shown). The live and dead levers are supported from the center sill by means of lever guides indicated at 25.

The center connection 17 includes two end sections indicated at 26 and 27 and the adjacent ends of said sections are screw-threaded to present right and left screw-threaded ends as shown at 28 and 29 respectively.

The screw-threaded ends 28 and 29 are connected by a screw-threaded take-up device 30 which includes a complementary screw-threaded turnbuckle 31 having tubular extensions 32 and 33 for supporting the rods at an appreciable distance from the screw-threaded portions of the turnbuckle. The extension 33 is provided with a pair of flanges 34—34 located in spaced relation on member 33 and welded thereto at 35.

A ratchet wheel member 36 is fixedly secured to the turnbuckle by welding as indicated at 37 and disposed at an appreciable distance from the flanges 34.

Rotation of the take-up device 30 in a take-up direction is effected through the medium of a bell crank lever 38 having an operating arm 38 on which a pawl arm 39 is pivotally mounted for up and down movement. The lever arm 38 is mounted to have swinging movement in a plane at right angles to the axis of rotation of the take up device and to this end is pivotally mounted on a trunnion 40 integrally formed on a saddle member 41. The saddle member 41 is in the form of an inverted U and includes a concave shaped seat 42 corresponding in shape to the circular shaped tubular extension 33 and the said U shape is extended to provide depending walls 43—43.

Figure 9 is a view of the outer end of the mechanism shown in Figures 7 and 8 except that the pawl is shown in position of release as the spring retaining escapement operates.

The saddle member 41 straddles the tubular member 33 with the concave seat seating on the circular shaped surface of the said member 33 and the walls 43—43 extend beyond the latter and are apertured to receive a cotter pin 44 whereby the saddle member is maintained in position against the take up member. The saddle member is disposed between the spaced flanges 34—34 and is thereby retained in axial alignment on the take up device.

The lever 38 is maintained in position on the trunnion 40 by a washer 45 which is secured in place against the face of the trunnion by a headed rivet 46 which extends through the trunnion and washer and is formed with a countersunk head 47. The lever is further supported on each side of its pivotal axis by means of webs 48—48 which lie at each side of the trunnion 40 and form an underlying support for the lever to prevent undue play between the parts. The lever 38 extends downwardly at an angle to pass beneath the cylinder and connect with spring mechanism as will hereinafter be described.

The pawl arm 39 is preferably formed of a circularly shaped bar which is bent to L shape to form angularly related arms indicated at 49 and 50 respectively, the former being disposed to sweep across the face of the ratchet wheel 36 and the latter is pivotally mounted in hollow tubular bearings 51—51 disposed at the side of the lever arm 38 and welded thereto at 52.

Intermediate the bearings 51—51, there is disposed a thrust member 53 which encircles the arm 50 of the pawl arm and is riveted thereto at 54. At the lower portion of the thrust member 53 there is welded at 55 a jawlike piece 56 having upper and lower faces as indicated at 56a and 56b and arranged and adapted to respectively contact the upper and lower faces of the arm 38 to limit rocking movement of the pawl arm.

The teeth of the ratchet wheel member 36 are of such a form as to present on one side a concave shaped pocket 57 and on the opposite side a convex shape contour 58 with a tangentially related slope 59 connecting the convex shape with the concave pocket of the next adjacent tooth. This arrangement of concave and convex surfaces in combination with a gentle connecting incline permits the arm 39 to ride above the teeth and independently thereof when the bell crank lever is swung in unison with the forward movement of the push rod and engaging the teeth when returned by the spring mechanism.

The outer end of the arm 38 which is slotted at 61 is extended outwardly towards the cylinder and beneath the same to connect with operating spring mechanism 62 which is disposed below the level of the push rod and between the latter and the center sill.

The spring mechanism 62 is supported at one end by a bracket 63 which is rigidly mounted on the cylinder at 64 and at the opposite end by a bracket plate 65 rigidly secured to the center sill and which extends outwardly and downwardly therefrom to support the opposite end of the spring mechanism.

The spring mechanism 62 includes a slide 66 consisting of a pair of rail members 67—67 which extends through a guide bracket 68 and adjacent the opposite end the slide is formed with a shoulder 69. Interposed between the shoulder 69 and the guide bracket 68 is a coil spring 70 which encircles the rails. Projecting beyond the shoulder 69 is a pair of jaws as indicated at 71 and 72 between which the outer end of the downwardly extending lever 38 is received and pivotally connected at 72a.

The rail members are maintained in spaced relation by a hollow tubular member 73 and a toothed block 74, said respective members being welded to the rails as indicated at 75 and 76 respectively. The member 73 is extended to project beyond the shoulder 69 and is welded thereto at 77 and to the upper jaw piece 72. The toothed block 74 which includes three teeth 78, 79 and 80 is disposed in proximity to the guide bracket 68.

Extending within the tubular section 73 is a supporting rod 81 which is formed with a vertically extending stem portion 82 which fits into the bracket 63 and is supported thereby. The guide bracket 66 includes a pair of side walls 83—83 and upper and lower walls 84 and 85 which combine to form an open ended box-shaped member to allow the rail portion of the slide to move freely therein.

The side walls 83—83 are extended downwardly to form lugs 86—86 between which a weighted pawl 87 is pivotally mounted, said pawl having a detent portion 88 arranged to successively engage with the teeth 78, 79 and 80 of the toothed block to hold the spring compression at various stages of piston travel.

The slide 66 being slidably mounted in the guide bracket 68 and the supporting rod 81 having sliding contact within the tubular center member 73 provides a telescopic effect which allows for self-adjustment in length between the stationary guide bracket 68 and the bracket 63 on the cylinder and thus allows for variations in the length of the push rod.

Compression movement of the spring is effected through the medium of an abutment 89 carried by the push rod 14 and said abutment extends downwardly to engage with the shoulder 69 of the spring mechanism. The abutment member 89 is in the form of an angle shaped bracket having in addition to the abutment wall 89 a horizontally disposed wall 90 arranged to overlie the upper surface of the upper jaw piece 91 of the push rod. The wall 90 is notched to present a concave shaped contour 92 conforming in shape to the outer contour 93 of a clevis 94 and the meeting edges of said walls 90 and the outer contour 93 of the clevis are welded together at 95 to form an integral structure. The abutment wall 89 is apertured at 96 for the accommodation of the stem 97 of the push rod 14, and the said aperture 96 is formed of slightly elongated shape by depressing a portion of the body of the plate as indicated at 98.

The formation of the abutment wall 89 in an integral structure with the clevis 94 thus provides a rigid one-piece structure supported by the stem of the push rod and by the pintle at a location above and below the jaws of the push rod. The fact that the aperture 96 is of elongated shape enables the threading of the abutment and clevis assembly at such an angle as to clear the jawed portion of the push rod, as best shown by reference to Figure 17.

The spring 70 is maintained under initial compression between the shoulder 69 and the guide bracket 68 by means of stops 99 which engage with the side walls 83—83 of the guide bracket. The spring mechanism assembly 62 may thus be applied in place as a unit with the shoulder 69 of the spring contacting the abutment wall 89 of the push rod, the telescoping character of the supporting bracket 81 allowing for variations in the length of the push rod.

The operation of the mechanism is as follows: Assuming the brake parts and slack adjuster mechanism to be in released position as shown in Figures 1, 3 and 7, the push rod moves forwardly upon the application of braking pressure taking along shoulder 69 of the spring mechanism by reason of the co-acting engagement between said shoulder and the abutment 89 of the push rod. The forward movement of the push rod is accompanied by a swinging movement of arm 38 as shown by conventional dot and dash lines indicated at 100 in Figure 18. Compression of the spring is held at various intervals of push rod travel by reason of the coacting engagement between detent 88 of the pawl 87 and teeth 78, 79 and 80 as shown in Figure 8.

Upon the push rod travel exceeding the required predetermined extent of travel the teeth override the pawl as shown in Figure 9 and the spring then returns to release position and swings the lever 38 on its pivot with the arm 39 engaging the seat 57 and thereby rotating the take-up device in a take-up direction, the pawl 87 meanwhile being moved to an overbalanced non-operative position by the returning slide 66 as shown in Figure 10. Upon complete release of the brake and spring mechanism the weighted pawl 87 returns to normal vertical release position and in readiness for the next braking operation.

I claim:

1. In a slack adjuster mechanism for the brake system of a car structure, said brake including a brake applying cylinder and a push rod actuated thereby, brake levers interconnected by a tie rod connection, one of said levers being pivotally mounted on the car structure and the other lever pivoted to the push rod, said tie rod connection including a screwthreaded section and a complementary screwthreaded rotary take up member cooperating therewith whereby the length of the connection is varied by rotation of the take up member in a

take up direction to shorten the rod and thereby take up slack in the system; a ratchet wheel secured to the take up member, a bell crank lever having angularly related arms and pivotally mounted on the take up member and having an arm adapted and arranged to have intermittent ratcheting engagement with the ratchet wheel upon swinging movement of the lever about its pivotal axis and having the other arm extending towards the push rod and beneath the brake cylinder; and a spring mechanism acting upon the last named lever arm for moving the same in a take up direction, said spring being energized by movement of the push rod in a brake applying direction and upon release of energy operating to effect movement of the related bell crank arm in a direction to take up slack, said spring mechanism having relatively stationary supporting members carried by the brake cylinder and car structure respectively and including a floating shouldered slide member telescopically related to said respective supporting members and having the spring encircling the slide member and disposed between the shoulder of the floating member and the supporting member on the car structure; and an abutment carried by the push rod arranged and adapted to engage with the shoulder of the slide member to energize the spring upon movement of the push rod in a brake applying direction.

2. In a slack adjuster mechanism for the brake system of a car structure including a live lever, a brake applying cylinder and a push rod actuated thereby, said push rod including an elongated stem portion with a jaw portion including a pair of jaws at the outer end straddling the live lever, a clevis straddling the jaws of the push rod and a pintle extending through the clevis jaws and live lever, a rotary take up member in the brake system for varying the relation between the brake parts by rotation of the device in a take up direction, a spring mechanism acting upon the rotary member for moving the take up device in a take up direction, said spring mechanism being energized by movement of the push rod and including a shoulder acted upon by the push rod when moved in a brake applying direction; the herein described improvement including an abutment member carried by the push rod, said abutment member being of angle shape and having one wall resting on the jaw portion at the end of the push rod and welded to the clevis and having the adjacent wall encircling the stem of the push rod and extending downwardly to engage with the shoulder of the spring mechanism.

3. In a slack adjuster mechanism for the brake of a car structure including a live lever, a brake applying cylinder and a push rod actuated thereby, said push rod including an elongated stem portion and a pair of jaws straddling the live lever and a clevis straddling the jaws of the push rod and a pintle extending through the clevis jaws and live lever, a tie rod connection pivotally connected to the live lever at an appreciable distance from the push rod, said tie rod connection including a screw-threaded section and a screw-threaded rotary take up member cooperating therewith whereby the length of the connection is varied by rotation of the device in a take up direction, a ratchet secured to the take up, a bell crank lever pivoted on the take up device and having an arm adapted and arranged to have intermittent ratcheting engagement with the ratchet and having the other arm extending towards the push rod and beneath the brake cylinder, and a spring mechanism acting upon the last named arm for moving the same in a take up direction, said spring being energized by movement of the push rod in a brake applying direction, the herein described improvement which includes spring mechanism having relatively stationary supporting members carried by the cylinder and car structure respectively and a floating shouldered slide member telescopically related to said respective stationary members; a spring encircling the slide and disposed between the shoulder of the floating member and the stationary member mounted on the car structure; and an abutment carried by the push rod arranged and adapted to engage with the shoulder of the spring mechanism, said abutment member being of angle shape and having one wall resting on the jaw end of the push rod and welded to the clevis and having the adjacent wall encircling the stem of the push rod and extending downwardly to engage with the shoulder of the spring mechanism.
